UNITED STATES PATENT OFFICE.

HENRY S. BREWINGTON, OF BALTIMORE, MARYLAND.

BOTTLE-CLOSURE.

No. 823,027.

Specification of Letters Patent.

Patented June 12, 1906.

Application filed September 6, 1905. Serial No. 277,195.

To all whom it may concern:

Be it known that I, HENRY S. BREWINGTON, a citizen of the United States, residing at Baltimore city, State of Maryland, have 5 invented certain new and useful Improvements in Bottle-Closures, of which the following is a specification.

My invention relates to an improvement in bottle-closures; and the object of my invention is to provide a closure which will seal and hold by friction within bottle-neck, as the bottles fail to run regular—that is, they are not all perfect—and by the use of my invention I provide a closure which will conform to the bottle-neck and make it air and gas tight.

My invention relates to certain other novel features of construction and combination of parts which will be hereinafter described, and 20 pointed out in the claims.

In the accompanying drawings, Figure 1 is a view of one form of closure; Fig. 2, a sectional view showing another form applied to a bottle, and Figs. 3, 4, 5, and 6 are modifications.

25 In Fig. 2, A represents the bottle-neck, and 1 is the cap or closure, made of aluminium or other suitable non-resilient material, and 4 is a packing.

30 In Fig. 3, 1 is a cup-shaped disk having an outwardly-turned top portion 2 and a flat bottom 3.

Fig. 4 is a modified form. 1 represents the cup-shaped disk; 4, a suitable packing; 5, a flange.

35 In Fig. 5, 1 is a modified form with a partially-turned flange without packing.

In Fig. 6, 1 is a modified form, 6 a modified closed bead under which a packing is placed at 7.

40 The cap or closure is preferably made cup-shaped, and when it is desired to seal a bottle the closure is forced down into the mouth of the bottle by means of a suitable tool, and the cap being of a non-resilient material it 45 will conform to the shape of the bottle-neck and forms a sealing as well as holding contact.

50 In the form shown in Fig. 5 the cap is placed in the bottle-neck by a downward pressure, and the top of the cup is made to lie flush with the top of the bottle-neck or to overlap it, thereby forming an air and gas tight closure. The bottom of the cup-shaped disk performs quite a function in that the

pressure to a certain extent is obtained from 55 the bottom in holding the sides strongly against the bottle.

In most instances, where the bottle is nearly perfect and in proper size, it will not be necessary to use any packing; but when 60 required a packing of any suitable material may be used, as shown in Figs. 2 and 4. Same can be applied in Fig. 6.

It will be seen from the foregoing that I have provided a cap or closure which may be 65 used on jars as well as bottles, and one which is absolutely air and gas tight, as by the use of aluminium it is non-resilient, and when the disk is forced in the bottle-neck it will conform thereto and make a tight sealing-contact.

It is evident that slight changes might be made in the form and arrangement of the several parts described without departing from the spirit and scope of my invention, 75 and hence I do not wish to limit myself to the exact construction here set forth; but,

Having fully described my invention, what I claim as new, and desire to secure by Letters Patent, is—

1. A bottle cap or closure in the form of a hollow cup shape disk, made of a non-resilient sheet metal, having a flat bottom, the walls of which are perpendicular thereto, a partially-closed flange at the top and adapted 85 to be spun or forced into and made to conform to the irregularities of the inner wall or bore of a bottle-neck.

2. A bottle-closure in combination with a bottle, in the form of a hollow cup shape disk, 90 made of a non-resilient sheet metal, comprising a flat bottom the walls of which are perpendicular thereto, and adapted to be forced into and made to conform to the irregularities of the inner wall or bore of the bottle-neck substantially as herein described.

3. A bottle-closure in combination with a bottle in the form of a cup-shape disk provided with a flat bottom the walls of which are perpendicular thereto, having an outwardly-turned portion formed on the top portion thereof, and adapted to be forced into the bore of the bottle-neck, made from non-resilient sheet metal that will conform to the irregularities of the inner wall or bore of the bottle-neck and form a sealing-contact substantially as herein described.

4. A bottle-closure in combination with a

bottle in the form of a cup-shape disk having an outwardly-turned portion formed on the top and a packing resting under the outwardly-turned portion and adapted to be forced into the bore of a bottle-neck, the packing resting on top of the mouth of the bottle beneath the outwardly-turned portion, made from non-resilient sheet metal that will conform to the irregularities of the inner wall or bore of the bottle-neck and form a sealing and holding contact.

5. A bottle-closure in combination with a bottle, in the form of a cup-shape disk, having a flat bottom, the walls of which are perpendicular to said bottom, an outer turned flange formed on the top part thereof, made of non-resilient sheet metal, which when forced within the bottle-mouth will conform to the irregularities of the inner wall or bore 10 of the bottle-neck and form a frictional and

sealing contact substantially as herein described.

6. A bottle-closure in combination with a bottle, in the form of a cup-shape disk, having formed an outwardly-turned flange on 25 the top part thereof, made of non-resilient sheet metal, a suitable packing beneath the outwardly-turned top flange which, when forced within the bottle-mouth will conform to the irregularities of the inner wall or bore 30 of a bottle-neck and form a frictional and sealing contact substantially as herein described.

In testimony whereof I affix my signature in presence of two witnesses.

HENRY S. BREWINGTON.
